UNITED STATES PATENT OFFICE.

CHARLES BRUDERLEIN, OF NEW YORK, N. Y.

MILK-BOTTLE SUPPORT AND LOCK.

Application filed March 20, 1924. Serial No. 700,642.

To all whom it may concern:

Be it known that I, CHARLES BRUDERLEIN, a citizen of the United States, and a resident of the city of New York, borough of Manhattan, in the county and State of New York, have invented a new and Improved Milk-Bottle Support and Lock, of which the following is a full, clear, and exact description.

10 This invention relates to milk bottle supports and locks and has for an object to provide an improved construction which will present a desirable support and at the same time will automatically lock a bottle 15 to the support.

Another object of the invention is to provide a combined lock and support for milk bottles wherein after the bottle has been placed in position and the cover moved to a 20 closed position, the parts are locked against the removal by any one without the use of a prescribed key.

A still further object of the invention is to provide a lock and support for milk bottles wherein the lock will not function unless a bottle is arranged on the support thus permitting the lock and cover to be moved to a 25 closed position without throwing the lock.

In the accompanying drawing—

30 Figure 1 is a top plan view of the device embodying the invention, the top covering plate being broken away for better illustrating the locking mechanism.

Figure 2 is a vertical sectional view 35 through Figure 1, approximately on line 2—2.

Figure 3 is a view similar to Figure 1 but showing the parts being actuated by a key.

Figure 4 is a fragmentary horizontal sectional view through Figure 2, approximately 40 on line 4—4.

Figure 5 is a horizontal sectional view 45 through Figure 2 on line 5—5, the same being in effect an inverted plan view of the cover and associated parts.

Figure 6 is a sectional view through Figure 4, approximately on line 6—6.

Referring to the accompanying drawing by numerals, 1 indicates the side of a house 50 or other support to which the device may be secured by suitable screws 2 passing through the plate 3, which plate is provided with ears 4 and 5 and with a supporting structure 6. This supporting structure as shown in Figure 4, is substantially U-shaped, the same being formed with a back portion 7 and side

portions or arms 8 and 9. These arms are provided with beveled portions 10 and 11 adapted to receive the bead 12 of the bottle 13. It will be understood that the bottle 13 is inserted from the right in Figure 4 and moved toward the left until it assumes the position shown in this figure. Before it can be inserted, however, the cover 14 must be raised.

At the outer ends of the arms 8 and 9, are provided notches 15 for receiving the respective locking catches 16 and 17. The cover or lid 14 is provided with a solid top section merging into a depending flange 18 and resting on the support 6. At the front, a shoulder 19 is provided which rests on the arms 8 and 9 while a depending portion 18' overlaps part of the arms 8 and 9 and fits into the notches 20 and 21 at the center of the front flange 18' and the same is formed with a block 22, though if desired, this block could be made separate and secured in place. Attached to the block 22 is a depending flange 23 of the plate 24, which plate is held in place by the screw 25 passing into the block 22 and also through suitable screws 25' extending upwardly into the cover 14.

The lock mechanism as hereinafter fully described, is arranged between the plate 24 and the cover 14 except the bell crank lever 26 which is pivotally mounted in place by a pivotal screw 27. This lever has the end 28 extending through slot 29 so as to be 30 acted upon by the spring 32. The end 30 of the bell crank lever 26 is provided with a cam 31 adapted to be engaged by the bead 12 of the bottle as the cover is moved to a closed position. As this action takes place, the inclined surface of the cam 31 causes the bell crank lever 26 to move against the action of spring 32 for causing the catches 16 and 17 to move into certain of the notches 15 (Figure 6.) When this has been done, the cover will be locked closed and can only be opened by a properly constructed key. As the spring 32 is compressed (Figures 1 and 3), the locking plate 33 is moved over, said plate carrying a depending latch 17 where by said latch is forced into one of the notches 15. In order that the latch 16 may be forced into the notch 15, said latch is carried by a locking plate 34 having a notch 35 for receiving one end of the lever 36, the opposite end of this lever fitting loosely in the notch 37 of plate 33. It will thus be

seen that the plates 33 and 34 move toward each other or away from each other simultaneous. A spring 38 is connected to the two plates 33 and 34 and continually acts 5 to pull the same toward each other to cause the latches 16 and 17 to move out of the notches 15.

After the plates 33 and 34 have been separated for causing the latches 16 and 17 to 10 enter the notches 15, these plates can only be separated by the insertion of a proper key, as for instance, key 39. This key is provided with an inclined section 40 adapted to engage the inclined portion 41 formed on 15 the plate 33. When the key 39 is forced directly inwardly, the portions 40 and 41 will co-act for causing the plate 33 to be moved against the action of spring 32 and, consequently, cause the catches 16 and 17 to 20 move a sufficient distance toward each other to be released from the notches 15 whereupon the cover 14 may be raised. Usually the cover will raise itself automatically as 25 the spring 32 is acting on the end 28 of bell crank lever 26 which in turn is causing the cam 31 to press against the bottle. After the cover 14 has been raised, the bottle may be freely moved outwardly to the right in 30 Figure 4. If the cover is again lowered to a closed position, the locking mechanism will not operate as the cam 31 does not strike an obstruction.

When the delivery man wishes to place 35 a new bottle in the support 6 or in case some one in the house desires to place a bottle in the support 6, the cover 14 may be readily raised without the use of a key, the bottle inserted and the cover forced to a closed position against the action of spring 32 whereby 40 the catches 16 and 17 will move to a locked position.

What I claim is:

1. A milk bottle support and lock, comprising a substantially U-shaped support 45 adapted to receive the neck of a milk bottle, a cover for said support hingedly connected therewith and locking means for locking the cover in a closed position, said locking means including a pair of catches, spring means 50 for moving said catches to an unlocked position, and a cam adapted to be operated by a bottle arranged on said support for moving said catches against the action of said spring.

55 2. A milk bottle support and lock, comprising a support formed substantially U-shaped so that a bottle may be inserted laterally, said support being provided with notches at the outer ends of its two arms, 60 a cover hinged to said support near the inner ends of said arms, and a locking struc-

ture for locking said cover closed, said locking structure including a pair of catches adapted to be moved into said notches, means operated by the milk bottle as the 65 cover is closed for causing said catches to be moved into said notches, and a key adapted to move said catches out of said notches against the action of said last mentioned means. 70

3. A milk bottle support and lock, comprising a pair of supporting arms adapted to receive the neck of a milk bottle, a cover hinged to said supporting arms and a lock for locking said cover, said lock including a pair of catches adapted to be moved to a locked position, means actuated by the milk bottle for moving said catches to a locked position, and a spring for normally holding said means against functioning 75 when there is no milk bottle on the support.

4. A milk bottle support and lock, comprising a pair of supporting arms adapted to receive the neck and upper part of a milk bottle, a notch arranged in one of said arms, a cover pivotally mounted on said supporting arms so as to be moved downwardly against the supporting arms and a lock for locking said cover in its lower or closed position, said lock including a cam adapted to 85 be pushed to one side by the milk bottle as the cover is closed, and a catch operated by said cam, said catch being adapted to be moved into said notch whereby said lid 90 cannot be raised. 95

5. A milk bottle holder and lock, comprising a pair of holding members, a cover for said holding members and a lock for locking the cover closed, said lock including a pair of latch members adapted to 100 interlock with the holding members, spring means for normally moving said latches to an unlocked position, a lever functioning to move said latches to a locked position, and a cam secured to said lever, said cam being 105 positioned so that the inclined face thereof will strike the milk bottle when the same is arranged on said supporting members and be moved to one side thereby for actuating said lever. 110

6. A milk bottle support and lock, comprising a pair of supporting members for receiving the upper end of a milk bottle, a covering member therefor, means adapted to be actuated by the milk bottle when the covering member is closed for locking the covering member in a closed position, and key operated means for unlocking the covering member while the milk bottle is on said supporting members. 115
